UNITED STATES PATENT OFFICE.

LEO DAFT, OF GREENVILLE, NEW JERSEY.

ELECTRIC LOCOMOTIVE-ENGINE.

SPECIFICATION forming part of Letters Patent No. 325,915, dated September 8, 1885.

Application filed January 11, 1883. (No model.)

To all whom it may concern:

Be it known that I, LEO DAFT, of Greenville, Hudson county, New Jersey, have invented a new and useful Improvement in 5 Electric Locomotive-Engines, of which the following is a full, true, and exact description, reference being had to the accompanying drawings.

In the attempts to make electric locomotive traction-engines it has heretofore been universally believed that owing to the small amount of power which could be directly exerted in the revolution of the armature of a motor, it was necessary to connect that armature with some reducing contrivance, whereby the greater motion and less force of the armature was converted into less motion and greater force on the driving-wheel. This intermediate contrivance necessarily involves 15 great loss of power in friction, and it is also attended with reduced velocity of the driving-wheel.

My invention relates to a device for obviating these difficulties by connecting the 20 revolving armature directly to the shaft of the driving-wheel, and it will be readily understood from the accompanying drawings, in which—

Figure 1 represents a vertical view through 25 the line x x of Fig. 2, and Fig. 2 a plan view of my apparatus through the line y y of Fig. 1. Fig. 3 represents a view, partly in elevation, showing the connections of the armatures, field-magnets, and reversing contrivance; Fig. 4, a plan view of the same.

A A represent the field-magnets, B the armatures, and C the commutators. As shown in this application, one field-magnet A is used to make fields for two armatures—one at either 40 end.

There are many ways of electrically connecting the armatures and field-magnets; but I prefer an arrangement by which the relation between the armatures and the field-magnet may be altered, thereby changing the 45 direction of rotation of the armatures. One form of switch suitable for accomplishing this result is shown in an application which I have made for Letters Patent on the 12th day 50 of August, 1882, Serial No. 69,179, to which I refer for a fuller drawing of the switch.

This switch is shown generally at T. The electricity from the rail or other conductor

enters this switch by the wire marked 1 from the insulated wheel K or from some 55 other suitable part; thence it passes by wire 2 to the commutator-brushes on the armatures; thence by wire 3 again to the switch, thereby enabling the reversal of the commutator-circuits with reference to the field-magnet; thence by wire 4 to the field-magnet, and from the field-magnet to the return-conductor. The wires 5 and 6 connect with the rheostat in the manner shown in my other application, by means of which the 65 speed may be varied. In certain cases I may use two or more armatures, as shown at B B', Fig. 4, in place of a single armature. In this case one commutator will serve to operate both armatures. The circuit going to the 70 second armature may be broken and closed by an independent switch, if desired. In certain cases, however, this alteration is not essential, and other methods may be employed—as, for instance, the shifting of the commutator-brushes upon the commutator. In other cases independent field-magnets may be employed for each armature, and this arrangement I intend to make the subject of an independent application. It will be understood 80 that the field-magnets are suitably supported on the truck. As shown, they are carried by brackets.

When desired, I may add additional field-magnets on the other side of the armatures 85 from the sides at which the field-magnet A terminates. These additional field-magnets will of course be suitably supported. I may also employ several armatures upon the same shaft for increased power, if I so desire. 90

What I claim as my invention, and desire to secure by Letters Patent, is—

The combination, with the track connected to the source of electricity, of a field-magnet, two armatures driven thereby, driving-wheels 95 supporting the engine, directly connected with the armatures, and adapted to receive the current from the track and circuit-connections, substantially as described, whereby the current from the track passes through the wheels 100 and to and through the armature and field-magnet coils, substantially as described.

LEO DAFT.
